SPRAY NOZZLE

William Hungate, Houston, Tex.

Application June 25, 1956, Serial No. 42,039

Term of patent 14 years

(Cl. D62—2)

Fig. 1 is a side elevation of a spray nozzle showing my new design;

Fig. 2 is a top plan view thereof; and

Fig. 3 is a front elevational view thereof.

I claim:

The ornamental design for a spray nozzle, as shown.
